(57) **CLAIM**

The ornamental design for an elevated pet feeder, as shown and described.

DESCRIPTION

FIG. 1 is a perspective view from the top vantage point of an elevated pet feeder showing our new design;

FIG. 2 is a top plan view thereof;

FIG. 3 is a front side view thereof, the back side view being identical;

FIG. 4 is right side view thereof; the left side view being identical; and,

FIG. 5 is a bottom plan view thereof.

The broken lines are for illustrative purposes only and form no part of the claimed design.
